UNITED STATES PATENT OFFICE.

PHILIP BERNARD, OF JEFFERSON, SOUTH DAKOTA.

HOG-WATERER.

No. 843,925.

Specification of Letters Patent.

Patented Feb. 12, 1907.

Application filed April 3, 1906. Serial No. 309,646.

To all whom it may concern:

Be it known that I, PHILIP BERNARD, a citizen of the United States, residing at Jefferson, in the county of Union and State of South Dakota, have invented a new and useful Hog-Waterer, of which the following is a specification.

The invention relates to improvements in hog-waterers.

10 The object of the present invention is to improve the construction of hog-waterers and to provide a simple and comparatively inexpensive watering device adapted to enable a considerable amount of water to be 15 maintained at a temperature above freezing in the coldest weather at the expenditure of a comparatively small amount of heat.

A further object of the invention is to provide a hog-waterer of this character adapted 20 to afford animals a clean drink at all times and capable of preventing the water from being fouled or wasted.

With these and other objects in view the invention consists in the construction and 25 novel combination and arrangement of parts hereinafter fully described, illustrated in the accompanying drawings, and pointed out in the claims hereto appended; it being understood that various changes in the form, proportion, size, and minor details of construction 30 within the scope of the claims may be resorted to without departing from the spirit or sacrificing any of the advantages of the invention.

35 In the drawings; Figure 1 is a side elevation of a hog-waterer constructed in accordance with this invention. Fig. 2 is a plan view of the same. Fig. 3 is a vertical sectional view. Fig. 4 is a detail perspective view of 40 the trough.

Like numerals of reference designate corresponding parts in all the figures of the drawings.

1 designates an outer wooden or metallic 45 jacket of rectangular or other form and provided at the top with a hinged cover or lid 2. Within the jacket is arranged a cylindrical tank 3 of suitable sheet metal. The tank is spaced from the top, bottom, and walls of the 50 jacket to provide an intervening air-space, which enables the tank to be enveloped in warm air, whereby the tank is rendered easy to heat. Also the intervening air-space between the jacket and the tank prevents rapid 55 radiation of heat from the tank. The tank may be supported by suitable brackets 3*,

and within the space 4 between the bottom of the tank and the bottom of the jacket is arranged a gasoline-burner 5, which is supplied with gasoline from an exterior tank 6 through a pipe or tube 7.

The jacket is provided with air inlet and outlet openings 8 and 9 to permit the passage of air for supporting combustion, and the pipe or tube 7, which is composed of vertical and horizontal portions, is provided with a valve 10 for controlling the flow of gasoline. The vertical and horizontal portions are connected at their adjacent ends by a T-coupling 11, having vertical arms. A removable plug 12 is screwed into the lower arm of the T-coupling and is adapted to be removed, whereby the gasoline may be drained from the tank or reservoir 6 without removing the latter from the jacket. The gasoline tank or reservoir 75 is preferably secured to the jacket by means of metal straps or bands 13, which embrace the tank or reservoir 6 at the upper and lower portions thereof.

On the exterior of the jacket is secured a 80 trough 14, constructed of galvanized iron or other suitable material and connected with the tank 3 by means of a short tube or nipple 15, which pierces the adjacent wall of the tank 3 and which extends through the jacket 85 and through the inner wall of the trough. The pipe or nipple 15 is threaded for the reception of nuts 16 and 17, arranged in pairs. The nuts 16 engage the wall of the tank 3, a suitable rubber gasket 18 being provided to 90 prevent leakage from the tank into the space between the same and the outer jacket. The outer pair of nuts engage the jacket and the trough, and a rubber gasket 19 is provided to prevent leakage at the outer portion of the 95 nipple or tube 15.

The trough, which is tapered downwardly, is open at the top, and it is composed of a back 20, a downwardly and inwardly inclined front 21, and tapering sides 22. A horizontal 100 partition 23 is arranged within the trough at an intermediate point to form the bottom of the upper space or compartment, into which the short tube or nipple 15 discharges.

The tank is provided with a conical or funnel shaped top 24, which has a central opening and from which depends a filling-tube 25. The tube extends downward in the tank to a point below the short tube or nipple which constitutes the outlet. When it is 105 desired to fill the tank 3, the short tube or nipple is plugged by a suitable stopper. The

top of the tank 3 is provided with an air-cock 26, which is then opened to permit water to flow freely into the tank through the filling-tube 25. Any suitable means may be employed, if desired, for indicating the height of water within the tank 3. After the desired quantity of water is supplied to the tank 3 the air-cock 26 is closed and the plug is removed from the short tube or nipple 15. The water will then flow from the tank into the trough until the outlet is submerged. Water will be supplied to the trough as rapidly as it is consumed by the animals. The hinged lid or cover is provided with an opening 27, which is normally covered by a slideable door 28, mounted in a suitable guide or way formed by spaced bars or cleats 29. The spaced bars or cleats, which are located at the opposite sides of the opening 27, are provided at their inner opposite edges with grooves to receive the side edges of the slideable door.

The jacket of the tank is provided at one side with an aperture, which is normally covered by a pivoted door or closure 30 and which is adapted to afford ready access to the burner. Suitable handles 31 are provided at opposite sides of the jacket to enable the hog-waterer to be readily carried from one place to another.

Having thus fully described my invention, what I claim as new, and desire to secure by Letters Patent, is—

1. An apparatus of the class described comprising an outer jacket having inlet and outlet openings at the upper and lower portions, an inner tank located within the jacket and spaced from the top, bottom and walls of the same to provide intervening air-spaces, a burner located in the space between the bottom of the tank and the bottom of the jacket,

an exterior reservoir mounted on the jacket at the back thereof and connected with the burner for supplying the same with fuel, an exterior trough located at the front of the jacket, a short tube or nipple piercing the tank and the trough and extending through the contiguous wall of the jacket, and means mounted on the short tube or nipple for clamping the tank and for engaging the jacket and the trough.

2. An apparatus of the class described, comprising an outer jacket, an inner metallic tank located within the jacket and spaced from the top, bottom, and walls of the same, an outer metallic trough arranged exteriorly of the jacket, a short tube or nipple piercing the inner tank and the trough and extending through the contiguous wall of the jacket, means mounted on the short tube or nipple for clamping the inner tank and for engaging the jacket and the trough, and a heating device located beneath the tank.

3. An apparatus of the class described comprising an outer jacket having a hinged lid, said lid being provided with an opening and having guides at opposite sides thereof, a sliding door mounted in the guides for covering the said opening, an inner tank located within the jacket and provided at the top with means for filling it, said means being located below the sliding door, and an exteriorly-arranged trough connected with the tank.

In testimony that I claim the foregoing as my own I have hereunto affixed my signature in the presence of two witnesses.

PHILIP BERNARD.
